INVENTOR:
Charles R. Rouse,
by Murray G. Boyer
Attys.

UNITED STATES PATENT OFFICE.

CHARLES R. ROUSE, OF SWISSVALE, PENNSYLVANIA, ASSIGNOR TO PENNSYLVANIA CRUSHER COMPANY, OF NEW YORK, N. Y., A CORPORATION OF NEW YORK.

CAGE-ADJUSTING MECHANISM FOR CRUSHING MACHINERY.

Application filed June 21, 1926. Serial No. 117,374.

My invention relates to crushing machinery for reducing ore, stone, coal and similar material, and while not limited thereto, it is especially applicable to crushing machinery of the type known as "hammer crushers."

The object of my invention is to provide simple and efficient means for readily adjusting the cage or screen of a hammer crusher structure or similar crushing mechanism with respect to the rotor element carrying the hammers or other form of crushing or reducing means; such cage or screen being normally disposed substantially concentric with respect to the axis of rotation of the rotor element or slightly eccentric thereto.

My invention comprises mechanism for effecting adjustment of the cage or screen with respect to the rotor element, and consists of means for effecting bodily movement of the cage laterally with respect to the rotor element, and means for effecting vertical movement of the means effecting lateral adjustment of such cage or screen, so that as a resultant of these two adjustments or movements, the cage or screen will be brought into the desired position relatively to the path of the ends of the hammers or other crushing members carried by the rotor element.

These and other features of my invention are more fully described hereinafter; reference being had to the accompanying drawing in which:

Figure 1, is a side elevation, partly in section, of one form of crushing machinery of the "hammer crusher" type to which my improvements have been applied.

Fig. 2, is an end elevation of the same, partly in section.

Fig. 3, is a fragmentary view illustrating a detail of construction, and

Fig. 4, is a sectional plan view of a portion of the structure shown in Fig. 2.

As is well understood, the rapidity of motion and the character of the material operated upon dulls the ends of the hammers employed in crushing machinery of the type to which my invention is applicable and in time reduces their length, so that eventually such hammers are either repositioned with respect to the disks of a rotor element carrying the same, so as to project to an extent equal to that when first employed, or new hammers are provided.

It will also be understood that between the

installation of new hammers or repositioning of the same, there are periods where the gradual wear of the hammers has increased the distance between the ends of the same and the surface of the cage or screen, and it is desirable that this distance shall be maintained substantially the same at all times, whether the position of the screen or cage is concentric with respect to the path of the hammers or is slightly eccentric thereto. To this end, the mechanism forming the subject of the present invention has been devised.

The form of hammer crusher illustrated, is substantially the same as that shown in the patent of Hartman and Borton, No. 1,361,054, Dec. 7, 1920, in which the cage or screen 1, is supported at one end by an adjustable rack rod (or rods) A pivotally connected thereto, which rack rod (or rods) may be operated by a sprocket (or sprockets) B, actuated by suitable gearing, as fully set forth in said patent. The rack rod (or rods) A is pivotally connected to the cage or screen at a, and the usual gearing is provided to actuate the sprocket (or sprockets) B, whose teeth b, are disposed in engagement with the teeth a', of the rack rod (or rods) A. The opposite end of the cage or screen is pivotally supported by a rod or shaft 2, extending across the machine, and the present improvements are directed to means for changing the position of the pivot shaft or rod 2, so as to effect changes in the position of the cage or screen with respect to the path of the hammers or other crushing means of the rotor element.

The rotor element, which moves in the direction of the arrow x, may comprise the shaft D, carrying disks E, to which hammers F, are pivotally connected, as indicated at f.

The pivot shaft or rod 2 is arranged for rotative movement with respect to the cage or screen and in addition to this rotative movement it may be bodily lifted. Adjacent the ends of the shaft 2, eccentrics 3 are mounted thereon, which eccentrics are adapted to seats 4, in the side frames 5 of the cage or screen, so that if rotative movement is imparted to said shaft 2 it will effect movement of the cage or screen. The eccentrics are shown in Figs. 1 and 3, as occupying a vertical position with respect to the shaft 2, and if motion is imparted to the shaft in the direction of the arrow z, for instance, which will bring the rear end of the cage toward

the rotor, there will be a slight drop of the front end of the cage; the rear end rocking on its pivotal connection a with the rack rod (or rods) A.

In order that rotary movement may be imparted to the shaft 2, the latter carries a worm-wheel 6 at one end of the same, which is turned by a worm 7, in a manner herein-after referred to. This operation effects, relatively speaking, lateral adjustment of the cage or screen with respect to the rotor element in the direction of the arrow z' . By reason of the fact that the pivot shaft or rod 2, is eccentrically mounted with respect to its connection with the cage or screen it will be understood, of course, that coincident with any movement of the screen or cage relatively to the rotor element, effected by rotative movement of said shaft 2, vertical movement will be imparted to said shaft, and with the eccentrics in the position indicated in the drawing prior to the commencement of this movement, the latter will be downward.

The worm-wheel 6, keyed to one end of the shaft 2, is provided with a hub 6^a, journaled in a box 8, mounted for vertical movement on the side wall g , of the crusher structure, and the opposite end of said shaft 2 is journaled in a similar box 8^a, arranged for vertical movement on the opposite side wall g' . These boxes 8 and 8^a are adapted to slideways formed by pairs of members 10; one of each pair being fixed to the side walls of the crusher structure, while the others are carried by a cross beam h . These boxes 8 and 8^a are grooved at the sides, as indicated at 10^a, for the reception of vertical guiding ribs 10^b, formed on said members 10.

The movable boxes 8 and 8^a disposed at the sides of the crusher structure are suspended from lifting mechanism whereby said boxes, together with the shaft 2, worm-wheel 6, and attendant parts, may be raised and lowered, as may be necessary. These boxes are arranged for direct vertical movement so that after any rotary movement of the pivot shaft or rod 2, to effect adjustment of the cage or screen in the manner described, any vertical movement accompanying such adjustment may be compensated for by raising or lowering said boxes 8 and 8^a.

In the arrangement forming the subject of my present invention and disclosed in the accompanying drawings, this raising or lowering of the boxes 8 and 8^a, is effected by arms 11, carried by a rock shaft 12, journaled in bracket bearings 12^a and 12^b; such shaft extending across the machine above and parallel to the shaft or rod 2. The arms 11, carry links 13, which are attached at their lower ends to the boxes 8 and 8^a. The end of said shaft 12, carries another arm 11^a, in the form of a segment of a worm-wheel, with teeth 14, for engagement by a worm 15, mounted on a shaft 16, disposed in fixed

bearings 16^a carried by the bracket 12^a; such shaft having the usual hand wheel 17, whereby it may be turned. When therefore, the desired lateral adjustment of the screen or cage with respect to the rotor structure has been effected by partial rotation of the shaft or rod 2, the vertical position of such screen or cage can be taken care of by operating the arm 11^a, to rock the shaft 12, whereby the arms 11 may raise or lower, as the case may be, the boxes 8 and 8^a and thereby dispose the cage or screen in the desired position with respect to the path of the hammers of the rotor element.

The worm 7, is carried by a shaft 19, journaled in bearing 19^a, depending from the box 8, and upon turning said shaft 19, by a hand-wheel 20, motion will be transmitted to the worm-wheel 6; thereby turning the rod or shaft 2, and through the eccentrics 3 carried thereby, shifting the position of the cage or screen.

In lieu of the rock-shaft with its arm and link connections and the segmental rack and worm, for imparting vertical movement to the boxes 8 and 8^a; screws or worms may be vertically disposed, and adapted to fixed nuts properly mounted in operative position at the sides of the machine, and such screws or worms may be operatively connected to the boxes 8 and 8^a, supporting the shaft 2. Or a rack and pinion device may be directly connected to said boxes 8 and 8^a. If lifting screws or worms or rack and pinion devices are employed to effect vertical movement of the boxes 8 and 8^a, means will be provided to operate the same in unison at each side of the machine.

In order that the shaft or rod 2, may have room for movement relatively to the side walls g and g' of the machine when shifted by the operation of the worm-wheel; such shaft or rod, projecting through said side walls, the latter are provided with openings G, which may be of any suitable contour.

It is desirable to have the eccentrics 3 as small as possible, and in order to increase the range of adjustment which may be imparted to the cage or screen upon rotation of the shaft 2, the latter may be offset or cranked as indicated at 2^a; the eccentrics being carried by the cranked portions. It will be understood, however that the cranking of the shaft may be omitted altogether, without affecting the scope of the invention, and that the cranked shaft may be employed without the eccentrics to effect adjustments in the position of the cage or screen. Such modifications are believed to be within the terms of the appended claims.

I claim:—

1. The combination, with a crushing machine having a cage or screen of the rigid type, and crushing means rotatable with respect to said cage, of rotative means oper-

atively connected to one end of the cage for effecting adjustment of the cage with respect to the rotatable crushing means, and independent means for shifting the position 5 of the cage-adjusting means; the resultant of the adjusting operations, placing the cage in the desired position with respect to the crushing means.

2. The combination, with a hammer crusher having a cage or screen of the rigid type and a hammer-carrying element rotatable with respect to said cage, of rotative means operatively connected to one end of the cage for effecting adjustment of the cage with respect to the hammer-carrying element, and independent means for adjusting the cage-adjusting means, the resultant of the adjusting operations placing the screen or cage in the desired position with respect to the path 20 of the hammers.

3. The combination, with a crushing machine having a rotary hammer structure movable on a fixed axis, and a cage of the rigid type substantially semicircular in contour 25 partly surrounding the hammer structure; said cage being pivotally hung at one end of the same, of rotative means for shifting the position of said pivot, and means for raising or lowering the pivot-shifting 30 means.

4. The combination, with a crushing machine having a rotary hammer structure movable on a fixed axis, and a cage disposed substantially concentric with respect to the hammer structure; said cage being pivotally hung at each end and one of said pivotal connections occupying a substantially fixed 35 position when the hammer structure is in action, of rotative means for changing the position of said relatively fixed pivot to adjust the cage relatively to the hammer structure, and means for imparting direct vertical movement to the mechanism for changing the position of said pivotal connection. 40

5. The combination, in a crushing machine having a rotary hammer element and a cage or screen structure disposed in cooperative relation with respect to said hammer element, of a shaft upon which one end of said cage is pivotally mounted, eccentrics carried by said shaft and journaled in said cage structure, a worm-wheel carried by said shaft, a worm for moving said worm-wheel whereby the position of said eccentrics may be changed to shift the position of the cage, movable supports for said shaft, and means for imparting vertical movement to said supports. 55

6. The combination, in a crushing machine having a rotary hammer element and a cage or screen structure disposed in cooperative relation with respect to said hammer element, of a shaft upon which one end

of said cage is pivotally mounted; said shaft having an offset portion, eccentrics carried by the offset portion of said shaft and journaled in said cage structure, a worm-wheel carried at one end of said shaft, a worm for moving said worm-wheel whereby the position of said shaft and its eccentrics may be changed to shift the position of the cage, movable supports for said shaft, and means for raising and lowering said shaft supports. 65 70 75

7. The combination, with a crushing machine having a screening cage of the rigid type, and crushing means rotatable with respect to said cage, of an eccentric member rotatable on a fixed axis and in pivotal engagement with one end of the cage for shifting the latter in one direction with respect to the crushing means, and independent means for shifting the position of said eccentric member vertically; the resultant of the adjusting operations placing the cage 80 in the desired position with respect to the crushing means. 85

8. The combination, with a crushing machine having a pivotally supported screening cage of the rigid type, and rotatable crushing means disposed within said cage, of an eccentric member rotatable on a fixed axis for moving the pivotal support for the cage to adjust the latter with respect to the crushing means, and independent means for imparting vertical movement to said eccentric member. 90 95

9. The combination, in a crushing machine having a rotary hammer element and a screening cage disposed in cooperative relation with respect to said hammer element, of a shaft upon which one end of said cage is pivotally mounted, eccentrics carried by said shaft and journaled in said cage structure, means for rocking said shaft whereby the position of said eccentrics may be changed to shift the position of the cage, movable supports for said shaft, and means for imparting vertical movement to said supports. 100 105 110

10. The combination, in a crushing machine having a rotary hammer element and a screening cage disposed in cooperative relation with respect to said hammer element, of a shaft upon which one end of said cage is pivotally mounted; said shaft having an offset portion, eccentrics carried by the offset portions of said shaft and journaled in said cage structure, means for rocking said shaft whereby the position of said eccentrics may be changed to shift the position of the cage, movable supports for said shaft, and means for imparting vertical movement to said supports. 115 120

In witness whereof I have signed this specification.

CHARLES R. ROUSE.
